UNITED STATES PATENT OFFICE.

JAMES R. SPEER, OF PITTSBURG, PENNSYLVANIA.

IMPROVEMENT IN SHEEP-PROTECTORS.

Specification forming part of Letters Patent No. **222,368**, dated December 9, 1879; application filed October 30, 1879.

To all whom it may concern:

Be it known that I, JAMES R. SPEER, of Pittsburgh, in the county of Allegheny and State of Pennsylvania, have invented a new and useful Improvement in Sheep-Protectors, the same being an improvement of the sheep-protector for which Letters Patent were granted to me June 3, 1879, No. 216,235; and I do hereby declare that the following is a full, clear, and exact description thereof, reference being had to the accompanying drawings, and to the letters of reference marked thereon.

My present invention consists of two collars for the neck of the sheep, which collars are provided with sharp-pointed projections, and are coupled together by two or more links. To the upper side of the rear collar is attached a chain, strap, or strip of metal or other material, which passes along the back of the sheep and branches off toward the thighs of the hind legs, and is attached to a shield on each hind leg, which shields conform to the parts of the hind legs above the knee, said shields being perforated and furnished with outward-projecting points.

To enable others skilled in the art with which my invention is most nearly connected to make and use it, I will proceed to describe its construction and operation.

In the accompanying drawings, which form part of my specification, Figure 1 is a side view of a sheep having my improved protector arranged on it. Fig. 2 is a top view or plan of the protector, representing the several parts united. Fig. 3 is a side view of the same.

In the accompanying drawings, A represents the front collar, and B the second or back collar. These collars are made in two parts, hinged together on the under side, (shown at *g*.) and are provided with projecting points, as at *e*. The collars are coupled together by links, as at *f*, and, when on the sheep, locked, as at *h*.

To the back edge, on the upper side of collar B, is attached a chain, C, which branches at *i*, which branches are attached to the shields D, for the hind legs of the sheep. The shields D are perforated and provided with sharp projections *k*.

The collars A B and shield D are constructed of sheet metal, and are represented as being held together with relation to each other on the sheep by means of small chains; but leather or metal strips may be employed for this purpose; also, wire cord, or hemp or cotton cord, may be used; but preference is given to wire chain.

The shields D are represented in combination with the two collars A B; but a single collar may be used in combination with the shields D, and form a very good protector.

It has been observed that dogs often attack sheep at the points covered by the shields D; hence the employment of them in combination with the collars A and B, or with the single collar A or B. The projections or points on the collars and shields operate to lacerate the mouth of the dog in case it should attack the sheep, the point of attack, as a rule, being the parts covered by the collars and shields.

Having thus described my improved sheep-protector, what I claim as of my invention is—

1. A sheep-protector consisting of the collars A and B and shields D, provided with suitable connections, substantially as herein described, and for the purpose set forth.

2. A sheep-protector consisting of a collar and shields D, provided with suitable connecting apparatus, substantially as herein described, and for the purpose set forth.

JAMES R. SPEER.
